UNITED STATES PATENT OFFICE.

WALTER JONES WILLSON, OF BOSTON, AND HENRY E. DIX, OF ARLINGTON, MASSACHUSETTS; SAID DIX ASSIGNOR TO SAID WILLSON.

DESIGN FOR A COPY-HOLDER.

No. 39,646.

Specification for Design.

Patented Oct. 27, 1908.

Application filed March 26, 1908. Serial No. 423,491. Term of patent 14 years.

To all whom it may concern:

Be it known that we, WALTER J. WILLSON and HENRY E. DIX, citizens of the United States, and residents, respectively, of Boston, county of Suffolk, State of Massachusetts, and Arlington, county of Middlesex, and State of Massachusetts, have invented a new, original, and ornamental Design for Copy-Holders for Holding Note-Books while Copying from them, of which the following is a specification, reference being had to the accompanying drawing, forming part thereof.

The figure is a view in perspective of a copy holder showing our new design.

The design comprises an oblong shaped base having situated centrally thereof a depression with a rounded bottom and having

either side of the depression a plurality of transversely-extending parallel grooves, said base also having adjacent each end a larger groove with a rounded bottom. The copy holder is used by opening the note book and folding the covers back on themselves and then inserting the edges of the covers in the grooves on opposite sides of the central depression.

We claim:

The ornamental design for a copy holder as shown and described.

WALTER JONES WILLSON.

HENRY E. DIX.
